UNITED STATES PATENT OFFICE.

CHARLES SKOGlund, OF LYNN, MASSACHUSETTS, ASSIGNOR TO GENERAL ELECTRIC COMPANY, A CORPORATION OF NEW YORK.

METHOD OF MAKING TUBING.

Application filed January 31, 1922. Serial No. 533,072.

My invention relates to a method of making tubing and has for its object the provision of a method of and apparatus for forming and treating tubing in a simple, reliable, and economical manner.

It is common in the making of various kinds of tubes, for example, varnished fabric insulating tubes, to insert a rod tightly in the woven fabric tube to support the fabric in tubular form while being treated. After the fabric has been treated the rod is removed, the fabric then having sufficient rigidity to be self-supporting. A great disadvantage in this method is that a solvent of some kind is necessary to free the rod from the tube in order to permit its removal. This results in deterioration of the treatment to which the tube has been subjected. By means of my invention, I have provided a method of making tubing, whereby it is not necessary to use a rod to support the material while being treated.

In carrying out my invention in one form, I provide flattened fabric tubing which I shape in tubular form by drawing it through a die, after which I maintain the fabric under tension to preserve its form and then treat it to give it rigidity. In one embodiment of my invention I force a ball through the flattened tubing while simultaneously therewith drawing the tubing through the die, whereby the fabric is in effect progressively ironed in tubular form.

For a better understanding of my invention reference should be had to the accompanying drawing in which Fig. 1 is an elevation view showing apparatus for making tubing in accordance with my invention; Fig. 2 is an end elevation view of the ironing device through which the tubing is passed; Fig. 3 is a sectional view along the line 3-3 of Fig. 2, looking in the direction of the arrows; while Fig. 4 is a view in perspective of the supporting frame on which the tubing is wound under tension.

Referring to Fig. 1 of the drawing, in one form of my invention, the flattened fabric or other tubing 10, wound on a suitable reel 11, is drawn under tension through an ironing device 12, which shapes the fabric in tubular form, and then wound under tension on a frame 13. The tubing is drawn through the ironing device 12 by suitable operating means (not shown) which is connected by a belt 14 to a driving wheel 15

secured to frame 13. By means of a tensioning device comprising plates 16 and 17 which can be adjusted with relation to each other by means of a thumb screw 18, any desired tension can be applied to the tubing, the tubing being passed between the plates 16 and 17.

Referring to Figs. 2 and 3, the ironing device 12 is provided with a die 20 having a round aperture through which the tube is drawn. The die is held in a suitable support 21 by means of a set screw 21'. Dies of various sizes may be provided for use with a single support. They can be exchanged to correspond with the size of the tubing by loosening screw 21'. Electric heating devices 22 and 23 are mounted in the support 21 adjacent the die so as to heat it to a desired working temperature. These heating devices may be of any suitable type, such as cartridge resisting units. They are shown as cylindrical in form and having their terminals extending from opposite ends, one pair of adjacent end terminals being connected by a conductor 24, while the opposite terminals are connected to a suitable source of electric supply (not shown) through conductors 25 and 26. The heating devices are thus connected in series relation, although any suitable arrangement may obviously be used.

A ball 30 is provided which is slightly larger than the diameter of the die. As the tubing is drawn through the die, this ball is forced through it. A cylindrical metallic member 31 is secured to frame 21 so as to surround the tube. Member 31 carries a receptacle 32 which is adapted to catch the ball when the end of the tubing is reached.

Referring to Fig. 4, the frame 13 upon which the tubing is wound comprises two parallel bars 33 and 34 having transverse rods 35 and 36 joining their adjacent extremities. Bars 33 and 34 are provided with central transverse openings 37 and 38 by means of which the frame is supported. Bar 34 fits snugly in a channel member 39 having a central pin 40 which extends through opening 38. The channel member is secured to a driving shaft 41 to which pulley wheel 15 is secured. Opening 37 in bar 33 is engaged by the end of a longitudinally movable rod 42, the outer end of which is provided with a ring 42'. Rod 42

carries near its end a collar 43 which is held against bar 33 by means of a spiral spring 44, the opposite end of which engages with the support 45 for the rod.

5 This arrangement provides for conveniently inserting and removing the frame 13. To remove the frame it is necessary only to pull the rod 42 outward by means of the ring 42' at its end against the tension of 10 spring 44 whereby the end of the rod is disengaged from bar 33 and the frame may be removed from channel member 39.

In making fabric tubing in accordance with my invention, a supply of untreated 15 woven fabric tubing is provided wound on reel 11. Such tubing is not sufficiently rigid to be self-supporting and collapses or flattens, having the appearance of a narrow strip. The end of the tubing is first passed 20 from reel 11 between clamping plates 16 and 17, ball 30 is then inserted, and the tubing passed through the die and secured in a suitable manner to frame 13, such as by tying it as shown at 46 (Fig. 3). Power is 25 then applied to pulley wheel 15 through belt 14 and the tubing drawn continuously through the die, which is maintained at a suitable working temperature by heating units 22 and 23, and wound under tension 30 on the frame 13. As the tubing is drawn through the die, ball 30 is simultaneously therewith forced through the tubing. When the frame is filled the end of the tubing is secured in any suitable manner, whereupon 35 the frame is removed and an empty one inserted in its place, the operation then being repeated as previously described.

Due to the joint effect of the die and the ball, the fabric is ironed inside and out in 40 tubular form as it is drawn through the die. The effect of the die in giving the fabric the desired tubular formation is, however, more pronounced than that of the ball. Under certain conditions the tubing may be 45 satisfactorily treated without the use of the ball, but I have found that it is often desirable to use the ball to smooth out any irregularities which may be found in the fabric. The heat applied expands the fibers of 50 the fabric and tends to set them as formed by the die.

The plates 16 and 17 are adjusted by thumb screw 18 so as to apply a tension to the fabric which is just sufficient to maintain it in tubular form after it leaves the die and when wound on the frame.

55 The tubing as supported on frame 13 is now subjected to a suitable treatment to give it rigidity, such as impregnation with a varnish to form electrically insulating tubes. The tubing is then dried, whereupon it may be removed from the frame and cut into tubes of the desired length, the fabric then being sufficiently rigid to be self supporting. It will be observed that each turn of

the tubing is flattened where it engages with transverse rods 35 and 36 on the frame. By using a correspondingly sized frame, any desired length of tube may be produced. Obviously by providing suitable supporting 70 means for maintaining the fabric under tension as it leaves the die, the tubing may be produced in continuous lengths. Furthermore, flattened tubing made of various materials other than fabric may be formed and 75 treated in accordance with my invention.

While I have described my invention as embodied in concrete form and as operating in a specific manner in accordance with the provisions of the patent statutes, it should 80 be understood that I do not limit my invention thereto, since various modifications thereof will suggest themselves to those skilled in the art without departing from the spirit of my invention, the scope of 85 which is set forth in the annexed claims.

What I claim as new and desire to secure by Letters Patent of the United States, is:—

1. The method of giving tubular form to 90 fabric tubing flattened into a ribbon which consists in drawing the flattened tubing through a die while applying a tension thereto, whereby the fabric is given a tubular form in passing through the die and 95 maintained by the tension in tubular form after leaving the die, and then impregnating the fabric to give it rigidity.

2. The method of giving tubular form to 100 fabric tubing flattened into a ribbon which consists in inserting a ball in the tubing, and then passing the tubing through a die so as to force the ball therethrough.

3. The method of giving tubular form to 105 fabric tubing flattened into a ribbon which consists in inserting a ball in the tubing and then drawing the tubing through a heated die in such manner that the ball is forced therethrough whereby the fabric is ironed inside and out in tubular form.

4. The method of making tubing which 110 consists in drawing flattened tubing through a die to give it form while applying a tension thereto sufficient to preserve its form after it leaves the die, and then treating the tubing after it leaves the die to give it rigidity.

5. The method of making tubing which 115 consists in drawing flattened tubing under tension through a heated die to give it form, maintaining the tubing under tension after it leaves the die to preserve its form, and then treating the tubing after it leaves the die to give it rigidity.

6. The method of making insulating tubing from flattened fabric tubing which 120 consists in drawing the flattened fabric tubing through a heated die to give it tubular form, maintaining the fabric under tension after it leaves the die to preserve its form,

and then impregnating the fabric with an insulating material to give it rigidity.

7. The method of making tubing which consists in progressively ironing flattened tubing inside and out to give it form, maintaining it under tension in the direction of its length to preserve its form, and then treating the tubing to give it rigidity.

8. The method of making tubing which consists in drawing flattened tubing through a die and forcing a ball therethrough to give it form, maintaining it under tension to preserve its form, and then treating the tubing to give it rigidity.

15 9. The method of making fabric tubing which consists in forming flattened fabric tubing by inserting a ball in the tubing and then drawing it through a heated tubular

die which is slightly smaller than the diameter of the ball, winding it under tension on a reel to preserve its tubular form, and then impregnating the fabric with a suitable compound giving it rigidity.

10. The method of making fabric insulating tubing from flattened fabric tubing which consists in inserting a ball in the flattened tubing, drawing the tubing through a heated die in such manner that the ball is forced therethrough whereby the fabric is ironed inside and out in tubular form, and then impregnating the fabric with an insulating material giving it rigidity.

In witness whereof, I have hereunto set my hand this 26th day of January, 1922.

CHARLES SKOGLUND.
